[57] CLAIM

The ornamental design for a reconfigurable toy spacecraft, as shown and described.

DESCRIPTION

FIG. 1 is a front perspective view of a reconfigurable toy spacecraft showing my new design;

FIG. 2 is a side elevational view thereof;

FIG. 3 is a rear elevational view thereof;

FIG. 4 is a bottom plan view thereof;

FIG. 5 is another perspective view of the design shown in FIGS. 1 through 4 in a robot reconfiguration.

FIG. 1.

FIG. 2.

FIG. 3.

FIG. 4.

FIG. 5.
